CLAIM

The ornamental design for an enclosure, as shown and described.

DESCRIPTION

FIG. 1 is a perspective view of an enclosure, showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a perspective view of the enclosure of FIGS. 1-7 shown in condition of use with additional enclosures shown in broken lines.

The broken lines shown in the Figures show portions of the enclosure that form no part of the claimed design. The broken line inner perimeter immediately within the solid line outer edge of FIG. 7 represents the bounds of the claimed design, and also forms no part thereof. In FIG. 8, the additional enclosures shown in broken lines showing the design in condition of use also form no part of the claimed design.
